UNITED STATES PATENT OFFICE

ANN WOLVERTON, OF NEW YORK, N. Y.

DESIGN FOR A LAVATORY

Application filed February 19, 1929. Serial No. 30,124. Term of patent 3½ years.

To all whom it may concern:

Be it known that I, ANN WOLVERTON, a citizen of the United States, and a resident of the city, county, and State of New York, have invented a new, original, and ornamental Design for Lavatories, of which the following is a specification, reference being had to the accompanying drawings, forming a part thereof.

I claim:—

The ornamental design for a lavatory as shown.

ANN WOLVERTON.
